UNITED STATES PATENT OFFICE.

SETH L. SHELDON, OF ITHACA, NEW YORK.

OPENING ATTACHMENT FOR CANS OR VESSELS.

SPECIFICATION forming part of Letters Patent No. 758,152, dated April 26, 1904.

Application filed March 16, 1903. Serial No. 148,105. (No model.)

To all whom it may concern:

Be it known that I, SETH L. SHELDON, a citizen of the United States of America, residing at the city of Ithaca, in the county of Tompkins 5 and State of New York, have invented certain new and useful Improvements in Opening Attachments for Cans or Vessels, of which the following is a specification.

This invention relates to improvements in 10 cans and similar vessels for packing and storing, and is more especially directed to an attachment therefor designed to facilitate the opening of cans to which the closures thereof are sealed with a hermetic joint.

15 The object of the present invention is to provide an attachment of the character mentioned which may be applied to cans or similar packing and storing vessels with but slight cost and by the use of which the joints between the bodies of the vessels and the closures may be readily opened to enable removal of the closures without the necessity of cutting the joints or by the employment of any implement other than the attachment.

20 A further object of the present invention is the provision of an opening attachment which while the vessel is sealed forms a permanent part thereof, and thereby prevents loss of the attachment, but which may be 25 readily detached and discarded from the can or other vessel supplied therewith immediately upon the vessel being opened.

25 A further object of the present invention is the provision of an opening attachment 30 which is so applied to the can as to open the same with a minimum degree of effort and which is designed to effect the opening of the joint between the body of the vessel and the closure without defacing or injuring the appearance of the closure, thus enabling the latter to be subsequently used with the vessel for closing the same.

With these general objects in view and others which will appear as the nature of the 45 improvements is better understood the invention consists, substantially, in the novel construction, combination, and arrangement of parts, which will be hereinafter fully described, illustrated in the accompanying drawings, and pointed out in the appended claim.

While the forms of the invention herein shown and described are what are believed to be preferable embodiments thereof, it is to be understood that the same are susceptible of various changes in the form, proportion, and 55 minor details of construction, and the right is therefore reserved to modify or vary the invention as falls within the spirit and scope thereof.

In the drawings, Figure 1 is a side elevation of a can provided with an opening attachment constructed in accordance with the present invention. Fig. 2 is a vertical transverse sectional view thereof. Fig. 3 is a top plan view of a can, illustrating another form 65 of application of the herein-described invention. Fig. 4 is a vertical transverse sectional view of the form shown in Fig. 3.

Referring to the drawings, the numeral 1 designates the body of a can which is of the 70 ordinary construction; but the rim of said body is provided with a circumferential groove 2, the latter being formed in said rim in any suitable manner.

The numeral 3 designates an ordinary cover 75 applied to the can-body 1 and extending over the rim of the latter to a sufficient extent to cover the groove 2. This cover 3 is designed to be sealed to the body 1 by the employment of a suitable medium, such as solder, in order 80 to provide a hermetic joint between the body 1 and the cover 3. As before premised, it is

the object of the present invention to provide means for opening the joint referred to without the necessity of defacing or impairing the 85 can or without the employment of knives for cutting the same, as is usual. To this end a releasing-strip 4, preferably in the form of wire, although any other form may be employed, is seated in the groove 2 and surrounds 90 the rim of the body 1, and the end of said strip 4 is passed through a perforation 5, formed in the rim of the body 1 adjacent to the groove 2, and is bent to form a hook 6, whereby the inner end of the releasing-strip 95 4 is securely held in engagement with the rim of the body 1, but by which said strip may be readily detachable and discarded from the can-body when the joint has been opened. The outer end of the releasing-strip 4 passes 100

through and is seated within a groove 7, formed in the outer side of the body 1 and extending obliquely to the plane of the groove 2, and said groove 7 terminates in a substantially 5 elliptical groove 8, which is also formed in the outer side of the body 1 in order to receive a finger-loop 9, formed at the outer extremity of the strip 4. Through the medium of the grooves 7 and 8 and the fact that the 10 extremity of the releasing-strip 4 is seated within said grooves it will be seen that said extremity lies beneath the surface of the can-body and does not, therefore, interfere with the application of labels to said body. Moreover, the sealing medium effectually holds the 15 extremity of the strip 4 within the groove 7, thus preventing the entrance of air through said groove and at the same time preventing removal of the extremity therefrom. When it is desired to open the joint, the finger-loop 20 9 is removed from the groove 8 and by applying pressure to said loop and pulling thereon that portion of the strip within the groove 2 is gradually pulled from said groove, which 25 effects breaking the hermetic joint, and this is continued until the joint around the entire circumference of the can has been broken, whereupon the cover 3 is free to be removed from the body 1. When this has been accomplished, the purpose of the releasing-strip 4 30 has been fulfilled, and through the detachable connection of the inner end, by means of the hook 6 and the perforation 5, said strip may be readily detached from the can-body and 35 discarded. It will thus be seen that the joint between the cover and the body is broken in a neat manner and without in any degree defacing or impairing the appearance of the can or the utility of the cover 3, and the latter, 40 therefore, may be subsequently used for closing the can-body.

In Figs. 3 and 4 is shown another application of the releasing-strip 4, and referring thereto it will be observed that the cover 3 45 in lieu of being applied to the exterior of the can-body 1 is set within the mouth thereof, and the rim of said cover is provided with a circumferential groove 10, in which the releasing-strip 4 is seated. As in the form 50 shown in Figs. 1 and 2, the inner end of the strip 4 passes through a perforation 11, formed in the rim of the cover 3, and terminates in a hook 12, while the outer end of the releasing-strip 4 passes through an oblique groove 13, 55 also formed in the rim of the cover 3, in order that the extremity of the strip 4 may pro-

ject at the outer side of the can. This extremity terminates in a finger-loop 14, which finger-loop, if desired, may also be seated in a groove of corresponding shape as in Figs. 60 1 and 2 in order to depress the finger-loop beneath the surface of the cover 3. In this form it will be noted that the releasing-strip 4 occupies a position between the can-body 1 and the cover 3, immediately beneath the 65 joint therebetween, and by grasping the finger-loop 14 and exerting pressure thereon it will be seen that the body of the strip 4 may be readily drawn through the joint, severing the same and releasing the cover 3 from its 70 sealed relation to the can-body 1. As in Figs. 1 and 2, after the joint has been broken the usefulness of the strip 4 has terminated, and this may be readily detached from the cover 3 by removing the hooked end therefrom 75 and the strip may then be discarded. This does not affect the appearance of the can body or cover, and the utility of the latter for closing the can-body is still preserved.

Having thus described the invention, what 80 is claimed as new, and desired to be secured by Letters Patent, is—

The combination with the body of a can or similar vessel, and the closure thereof, one of said elements having a circumferential 85 groove provided with a perforation, of a releasing-strip seated in said groove and having a hook at its inner end which engages the perforation of said groove, whereby the inner end of said strip is detachably held, the other 90 end of said strip projecting between the body and closure to the exterior of the can and seated in a groove formed in the exterior of the side of the can and extending obliquely to the plane of said circumferential groove, 95 said end terminating in a finger-loop, the side of the can being also provided at its exterior with a groove corresponding to the shape of said finger-loop and communicating with the oblique groove, the finger-loop being seated 100 in said groove to position said loop and the extremity of the releasing-strip beneath the surface of the side of the can-body and thereby not interfere with application of labels to the body.

In testimony whereof I hereto affix my signature in presence of two witnesses.

SETH L. SHELDON.
